UNITED STATES PATENT OFFICE

ERNST KOENEMANN, OF HALENSEE NEAR BERLIN, GERMANY

ART OF HEATING STEAM BOILERS AND SIMILAR APPARATUS

No Drawing. Application filed January 21, 1930, Serial No. 422,498, and in Germany January 4, 1929.

The advantages attainable by transmitting in high-pressure boilers and other boilers subjected to a great stress the heat of the heating gases to the liquid to be evaporated not 5 directly, but by the intermediary of an auxiliary liquid are known. However, the advantages of such indirect heating systems are in some cases partly offset and in other cases even wholly offset by the great difficulties 10 connected with the finding out of an auxiliary liquid actually suited for the purpose in view, as all known auxiliary liquids hitherto used for that purpose are either decomposed at the higher temperatures concerned or become 15 solid at a relatively high temperature and change their volume; besides, nearly all those auxiliary liquids affect the material of the boiler shell and other apparatus, and indeed, some of them must be scrupulously avoided 20 on account of their poisonous character or their tendency to cause explosions. The same difficulties are the reason for the uselessness of normal auxiliary liquids for the heating of superheaters, intermediate superheaters, 25 and feed-water heaters. Finally, also molten metal salts have proved useless from the reasons stated.

All drawbacks stated in the preceding paragraph are completely avoided by using as an 30 auxiliary liquid a molten metal salt to which small amounts of ammonia have been joined.

Thorough tests have proved the fact that one succeeds in the just mentioned manner 35 in producing a heat carrier which even at high temperatures does not affect normal boiler material. By suitably selecting the metal salts for the purpose in view—metal chlorides are particularly suited—as well as 40 the amount of the adjoined ammonia, it is also possible to obtain a molten mass that can be heated sufficiently high without decomposing or forming steam. Moreover, the temperature at which the molten mass solidifies 45 can be considerably reduced, and it is possible to carry out the method in such a way that the mass solidifies without any material change of its volume, and even so that it solidifies in an amorphous manner like 50 glass.

While my invention contemplates such equivalent substances as will be suggested to the ordinary skilled chemist by my general disclosure herein, and by the following specific example of a complex compound of 55 a metal salt with a neutrally combined additive constituent separately gaseous at normal conditions, such specific example is particularly desirable and preferred by reason of its cheapness. This particularly well suited 60 substance is chloride of zinc to which so much ammonia has been adjoined that a mixture of chloride of zinc-monammoniacate

(ZnCl₂(NH₃))

65

and chloride of zinc-diammoniacate

(ZnCl₂(NH₃)₂)

is formed in which the chloride of zinc-monammoniacate predominates, suitable proportions of this mixture for heating at about 350° C. and atmospheric pressure being about 35% diammoniacate and 65% monammoniacate. This mixture is advantageous because it has a high coefficient of heat transfer, a 70 low viscosity and a low critical velocity as compared with compounds heretofore used as indirect heating liquids, such as fuel oil or glycerin. Furthermore, a large operating 75 temperature range is available with the mixture in molten state, as the boiling point or decomposition temperature of the molten mixture under atmospheric pressure, depending upon the content of ammonia, is from about 570° F. to 930° F. (300° C. to 500° C.) while it is still usably fluid at temperatures as 80 low as 250° F. (120° C.).

Particular advantages are attained if the auxiliary liquid is used for the heating of intermediate superheaters that must be arranged at some distance from the furnace, as in the immediate neighbourhood of the engine. Under these circumstances the conditions under which the auxiliary liquid solidifies are of particular importance, as, on the one hand, owing to the distance between the service members concerned, the solidification 85 of the auxiliary liquid can take place particularly easily, and on the other hand, greatest care must be taken that damages result- 90

95

100

ing from, or difficulties caused by, starting parts containing solidified liquid are absolutely prevented. Another point to be paid attention to is the slight viscosity of the new 5 heat carrier whereby the resistance to movement in the supply and the discharge pipes etc. and along the heating surfaces is reduced, and finally also the favorable behaviour of said heat carrier as regards the 10 transmission of the heat.

When making use of the present invention, the reconstruction of low-pressure boilers to high-pressure boilers entails particularly low costs, as the old boilers can be used again in 15 connection with the auxiliary liquid without any material change, the temperature in the boiler becoming higher, it is true, but the stress to which the boiler is subjected by the internal overpressure being obviated. It is 20 then sufficient to provide a high-pressure evaporator, or two or more such evaporators, in the neighborhood of the old low-pressure boiler or boilers and to transmit the heat from this or these latter to the high-pressure 25 evaporator or evaporators. There is requisite in most of these cases solely the erection of the cheap high-pressure evaporator or evaporators to be heated by the heat-transmitting auxiliary liquid, and the erection of an auxiliary or series turbine which is also cheap.

As above noted, my invention contemplates such equivalents as will be suggested to the skilled chemist by my present disclosure; and this fact is to be considered in connection 35 with the following claims.

I claim:

1. The method of heating steam boilers and similar apparatus by the intermediary of a heat-transmitting auxiliary liquid or liquefied substance, consisting in using as such substance a medium liquid throughout the temperature and pressure ranges of use and consisting of a metal halide other than a fluoride to which an appropriate amount of ammonia 40 has been adjoined to form a complex compound with the adjoined ammonia as a neutral part, substantially as set forth.

2. The method of heating steam boilers and similar apparatus by the intermediary 50 of a heat-transmitting auxiliary liquid or liquefied substance, consisting in using as such substance molten chloride of zink, to which so much ammonia has been adjoined that a mixture of chloride of zink-monammoniacate and chloride of zink-diammoniacate arises.

3. The method of transmitting the heat of a furnace to steam to be superheated in an intermediate superheater located at the place 60 of use of the superheated steam, consisting in transmitting the heat by the intermediary of a medium liquid throughout the temperature and pressure ranges of such use and consisting of a metal halide other than a fluoride to 65 which an appropriate amount of ammonia has

been adjoined to form a complex compound with the adjoined ammonia as a neutral part, substantially as set forth.

4. The method of transmitting the heat of a furnace to steam to be superheated in an 70 intermediate superheater located at the place of use of the super-heated steam, consisting in transmitting the heat by the intermediary of molten chloride of zink, to which such an amount of ammonia has been adjoined that 75 a mixture of chloride of zink-monammoniacate and chloride of zink-diammoniacate arises.

5. An indirect heating system employing 80 as the heat carrying medium a molten mixture of chloride of zinc-monammoniacate and chloride of zinc-diammoniacate.

6. An indirect heating system employing as the heat carrying medium a molten mixture of ammoniacates of zinc chloride. 85

7. An indirect heating system employing as the heat-carrying medium a molten mixture of two adjacent ones of the compounds of the series extending from zinc-chloride through the zinc-chloride ammoniacates. 90

8. An indirect heating system employing as the heat-carrying medium a molten mixture of two adjacent ones of the compounds of a series extending from a zinc-halide other than a fluoride through the ammoniacates 95 thereof.

9. An indirect heating system employing as the heat-carrying medium a molten mixture of two adjacent ones of the compounds of a series extending from a metal-chloride 100 through the ammoniacates thereof.

10. An indirect heating system employing as the heat-carrying medium a molten mixture of two adjacent ones of the compounds of a series extending from a metal-halide 105 other than a fluoride through the ammoniacates thereof.

11. An indirect heating system employing as the heat-carrying medium a molten mixture of ammoniacates of a zinc-halide other 110 than the fluoride.

12. An indirect heating system employing as the heat-carrying medium a molten mixture of ammoniacates of metal-chloride.

13. An indirect heating system employing as the heat-carrying medium a molten mixture of ammoniacates of metal-halides other than fluorides. 115

14. An indirect heating system employing a heat-carrying medium consisting of a mixture of addition compounds of zinc-halides other than fluorides with ammonia as an additive neutrally combined constituent. 20

15. An indirect heating system employing a heat-carrying medium consisting of a mixture of addition compounds of metal-halides other than fluorides with ammonia as an additive neutrally combined constituent. 125

16. An indirect heating system employing as the heat-carrying medium a molten mix- 130

ture essentially consisting of chloride of zinc-monammoniacate and chloride of zinc-diammoniacate.

17. An indirect heating system employing 5 as the heat-carrying medium a molten mixture essentially consisting of ammoniacates of zinc-chloride.

18. An indirect heating system employing 10 as the heat-carrying medium a molten mix-

ture essentially consisting of metal-chloride-monammoniacate and metal-chloride-diammoniacate.

19. An indirect heating system employing 70 as the heat-carrying medium a molten mixture essentially consisting of ammoniacates of metal chloride.

In testimony whereof I affix my signature.
ERNST KOENEMANN.

CERTIFICATE OF CORRECTION.

Patent No. 1,916,172.

June 27, 1933.

ERNST KOENEMANN.

It is hereby certified that error appears in the printed specification of the above numbered patent requiring correction as follows: Page 1, line 43, for "steam" read "vapor"; and that the said Letters Patent should be read with this correction therein that the same may conform to the record of the case in the Patent Office.

Signed and sealed this 22nd day of August, A. D. 1933.

M. J. Moore.
